UNITED STATES PATENT OFFICE.

PAUL ELGIN RIDINGS, OF TARKIO, MONTANA.

PRINTING MACHINE.

Application filed March 31, 1921. Serial No. 457,177.

To all whom it may concern:

Be it known that I, PAUL E. RIDINGS, a citizen of the United States, and a resident of Tarkio, in the county of Mineral and State of Montana, have invented a new and useful Improvement in Printing Machines, of which the following is a full, clear, and exact description.

My invention relates to machines for printing photographic prints from film negatives and it consists in the combinations, constructions and arrangements herein described and claimed.

An object of my invention is to provide a device designed for use particularly in the printing commercially of prints from film negatives and having means by which the printing operation may be greatly facilitated.

A further object of my invention is to provide a device of the type described that is adapted to accommodate film negatives and print papers of various sizes.

A further object of my invention is to provide a device of the type described that has means capable of being adjusted to vary as desired the widths of the margins on the completed prints.

A further object of my invention is to provide a device of the type described that is adapted to accommodate separate film negatives or a strip of connected film negatives.

A further object of my invention is to provide a printing device having a mechanism arranged to be operated automatically when the prints are made to number each print, if desired.

A further object of my invention is to provide a printing device having means for holding the paper to be printed in operative position until the paper has been printed and then for releasing the printed paper.

A further object of my invention is to provide a device of the type described, in which a platen carrying the paper to be printed and means of controlling the operation of the light producing means in the device are arranged so that the light producing means can only be energized after perfect contact between paper and film is made, and is de-energized before contact between paper and film is released.

A further object of my invention is to provide a device of the type described that is thoroughly effective for the purpose intend-

ed, can be operated readily, and is not likely to get out of order easily.

Other objects and advantages will appear in the following specification, and the novel features of the invention will be particularly pointed out in the appended claims.

My invention is illustrated in the accompanying drawings, forming part of this application, in which—

Figure 1 is a longitudinal section through the device, portions being shown in section and other portions being broken away,

Figure 2 is a plan view of the device,

Figure 3 is a plan view, showing the top portion of the device in raised position,

Figure 4 is a side elevation, partly in section, showing a fragmentary portion of the device.

Figure 5 is a sectional view through a portion of the device along the line 5—5 of Figure 2,

Figure 6 is a similar view of another portion of the device along the line 6—6 of Figure 2,

Figure 7 is a similar view through still another portion of the device along the line 7—7 of Figure 2,

Figure 8 is a detail of a fragmentary portion of the device,

Figure 9 is a section along the line 9—9 of Figure 2,

Figure 10 is a side elevation of a fragmentary portion of the mechanism shown in Figure 1,

Figure 11 is a section along the line 11—11 of Figure 1, and

Figure 12 is a section along the line 12—12 of Figure 3.

In carrying out my invention, I provide a frame having side members 1—1, end members 2 and 3, respectively, and a top consisting of a horizontal section 4 at the forward end of the frame and an inclined section 5 hinged at 6 to the end member 3 at its upper edge and adapted to rest upon the upper edges of the side frame members 1—1. The frame is made of any suitable material, preferably wood, and in the present instance is supported by a flat member, such as a table top 7 having a cavity 8 in its upper surface to which the frame is adapted so that movement of the latter relative to the table 7 will be prevented. The frame members 1—1, 2, 3 and 4 are secured together in any suitable manner.

The inclined top section 5 is formed with

an opening 9 therethrough, the walls of which have an inwardly extending continuous rib 10. A plate 11 of transparent material, such as a pane of glass, is mounted in the opening to rest upon the rib 10, being secured in position in any suitable manner so that the upper surface thereof is flush with the upper surface of the top section 5. A metal case or cabinet 12 that is open at its upper end is formed with a laterally extending flange 13 at its upper edge secured at 14 to the under surface of the top section 5 around the opening 9 so that rays of light from illuminating means disposed within the cabinet 12 will be projected upwardly through the transparent member 11, the inner walls of the cabinet being preferably finished to reflect rays of light upwardly. The cabinet 12 is provided with a door 15 that consists of a portion of a side wall of the cabinet hinged to the bottom at 16 and normally maintained in closed position by a catch 17 engaging with the stationary portion of the side wall. It will be noted that the cabinet 12 depends within an opening 18 through the table top 7 and that access to the interior of the cabinet may be had when the closure 15 is open so that illuminating means may be operatively installed within the cabinet. The illuminating means embodied in the device and the means provided for controlling the operation of the same will be described in detail hereinafter.

In the operation of the device, the film negative is disposed across the transparency 11 and a sensitized paper upon which the photographic impression is to be made is moved into the proper position relative to the negative to be printed therefrom when the rays of light from the illuminating means within the cabinet are projected upwardly through the transparent plate 11. To move the sensitized paper into position to be printed, I provide a platen 19 (see Figures 1, 2 and 7) that is formed of any suitable material, such as wood and is fashioned with parallel extensions 20-20 to the rear edge thereof, which form hinge members that are connected at 21-21 by a spring joint to cooperating hinge members 22-22 secured adjacent their rear ends by screws 23 or the like to the inclined top section 5. A bolt 24 is projected through each of the hinge members 22-22 adjacent its forward end and through the section 5, as shown best in Figure 7. A spring 25 is mounted on the bolt 24 between a washer 26 thrust upwardly thereby against the under surface of the section 5 and a washer 27 that rests upon a nut 28 screwed on the bolt 24 so that the forward ends of the hinge members 22-22 may be raised upwardly against the tension of the springs 25 and the face or under surface of the platen 19 will thus contact evenly along its entire surface with the

contiguous underlying surface when papers of various thicknesses are interposed therebetween. The spring joints 21 between the extensions 20-20 and the hinge members 22-22 tend to maintain the platen 19 in its raised position against a platen rest 29 that is secured at 30-30 to the section 5 adjacent the rear edge thereof. The face of the under surface of the platen 19 is covered with a suitable material, such as felt 31 that is sufficiently yieldable to closely contact with the entire surface of the work engaged.

The platen 19 is designed to be operated manually and so that the same may be quickly and easily moved from the position indicated by the dotted lines in Figure 7 to the position illustrated in Figure 1, I provide a handle 32 that is carried between the arms of a U-shaped frame 33 that is hingedly secured at 34 to the reverse side of the platen 19 along its forward edge. The hinge 34 is provided with a stop lug 35 arranged to prevent movement of the handle 32 from the position illustrated in Figure 7 toward the rear end of the platen while permitting movement of the handle in the opposite direction or forwardly.

The sensitized paper to be printed is carried by the platen 19. In order that the same may be maintained in adjusted position until the printing thereof has been completed, I provide a paper clamp carrier 36 comprising a substantially U-shaped body portion having the web thereof disposed transversely across the upper surface of the platen along its rear edge and having parallel arms 37 extending across the side walls of the platen and formed integral with laterally extending arms 38-38 which are pivoted at 39-39 to the side walls of the platen adjacent the forward end thereof. The paper clamp carrier 36 has three integral clips 40, 40' and 41 extending transversely across the rear end wall of the platen so that lateral extensions 42, 42' and 43 respectively thereof are moved into contact with the face or under surface of the platen 19 along its rear edge to clamp work to the under surface of the platen when the paper clamp carrier 36 is in a certain position relative to the platen. A plurality of bolts 44 are projected through the platen 19 so that the ends thereof extend through the openings in the web 36, the heads of the bolts being counter-sunk in the under surface of the platen. Springs 45 mounted on the bolts 44 and seated in sockets 46 in the upper side of the platen react against the under surface of the web of the paper clamp carrier 36, tending to move the latter upwardly against nuts 47 screwed on the ends of the bolts 44 and maintaining the integral clips in position to clamp the paper to the platen. A fourth paper clamping clip 48 is disposed contiguous to one of the

side walls of the platen and has the form of a bell crank lever pivoted between lugs 49 secured to one of the extensions 38 to the paper clamping member. One of the arms of the bell crank lever 48 normally abuts the adjacent arm 38 while the other arm of the bell crank lever extends at right angles thereto and has projected through an opening therein, a bolt 50 that engages a threaded opening in a lug 51 secured to the platen in any suitable manner as at 52. A second bolt 53 has its end projected through the arm of the bell crank lever 48 that normally abuts the adjacent arm 38 and is fastened at its end in the latter. A spring 54 disposed on the bolt 53 between its head and the arm of the bell crank lever normally holds the latter in the position indicated by the full lines in Figure 9.

The paper clamp carrier 36 is maintained in the position relative to the platen illustrated in Figure 9 when the latter is in raised or lowered positions. When the platen 19 is moved from the position shown in Figure 2 toward the position indicated by the dotted lines in Figure 7, a lug 55 that is integral with the web of the paper holding clamp is engaged by a thrust member 56 that is pivotally connected at 57 to an arm 58. The latter is pivoted at one end at 59 to a lug 60 secured to the section 5 of the top as at 61 and is connected by a link 62 at its other end to an upstanding lug 63 that is secured at 64 to the upper surface of the platen 19. As stated, the thrust member 56 engages the lug 55 when the platen is moved upwardly from the position illustrated in Figure 2 and the paper clamp carrier 36 is thereupon moved into the position shown in Figure 7 against the tension of the springs 45 so that the clips 40, 40', 41 and 48 no longer engage the work which is free to move on account of gravity along the inclined section 5 toward the section 4 of the top. A tension spring 65 has a connection at 66 with the arm 58 and a connection at its other end with the thrust member 56 so that the thrust member is moved out of engagement with the lug 55 when the platen has been moved into the position indicated by the dotted lines in Figure 7 and will be maintained out of engagement with the lug 55 until the platen has been moved into the position shown in Figure 1. At that time, the thrust member 56 will engage the lug 55 but obviously no pressure will be exerted on the latter until the platen is raised. A second thrust member 67 that is similar to the thrust member 56 is pivoted at 68 to a lug carried by the platen rest 29 and is maintained by a spring 69 against a stop 70 integral with the platen rest so that the thrust member 67 will engage the lug 55 when the platen is moved into the position indicated by the dotted

lines in Figure 7 to force the paper clamping member 36 into the position indicated by the dotted lines in Figure 7 so that the paper to be printed may be placed in adjusted position and will be firmly clamped by the clips 70 when the platen is moved forwardly.

It is important in order that the printing operation may be facilitated that the illuminating means be actuated coincidently with the operation of the platen. I therefore mount in sockets 71 secured within the case 5 to the bottom thereof, a plurality of incandescent lamps 72 arranged about an auxiliary incandescent lamp 73. The latter is continuously energized while the device is in use to allow film negatives to be properly adjusted. The incandescent lamps 72 are operatively connected in a circuit having electrical conducting wires 74-74 extending through the wall of the case 12 and connecting with spaced apart contacts 75 and 76, the connection being effected by means of binding posts 77 and a suitable insulation 78 being interposed between the wall of the case 12 and the contacts 75 and 76. Cooperating contacts 79 and 80 are spaced apart and connected by a suitable insulating member 81 to which is secured a clamp 82 having a push rod 90 projecting through a cross bar 83 that is slidably mounted on upstanding parallel rods 84 and 85 and is normally maintained in elevated position by the action of compression springs 86 disposed on the rods 84 and 85 between the cross bar 83 and the insulation 78 with which the rods 84 and 85 engage at their lower ends. The action of the springs 86-86 therethrough tend to maintain the connectors 79 and 80 out of engagement with the contacts 75 and 76 and the cooperating contacts 87 and 88 which are secured to the insulating material 78 in position to be engaged by the connectors 79 and 80 coincidently with the engagement of the latter with the contacts 75 and 76. An electrical conducting member, such as the insulating wire 89 connects the contacts 87 and 88.

The push rod 90 extends through an opening in the housing 91 for the switch mechanism described and as stated, extends through a registering opening in the cross arm 83. A disk 92 rigidly mounted on the push rod 90 abuts the cross arm 83 so that movement of the push rod inwardly will occasion a like movement of the cross arm 83 against the tension of the springs 86-86 and thereby cause the engagement of the connectors 79 and 80 respectively, with the cooperating contacts 75 and 87, and 76 and 88, thereby closing a circuit and energizing the incandescent lamps 72. It is to be understood that the lamps 72 and the lamps 73 are connected by electrical conducting means (not shown) with any convenient source of electric current supply. An operating arm 120

93 that is intermediately pivoted at 94 to a lug 95 secured to the under surface of the section 5 and extends through a slot 97 in the latter is arranged with its lower end portion 5 engaging the push rod 90 and with its upper end portion engaging a thrust rod 98 that is 10 slideable in openings through upstanding arms of a guide member 99 secured to the upper surface of the section 5 and is formed 15 at its other end for engagement with a second push rod 100. The latter is slideable in a guideway 101 extending through the platen 19 intermediate the upper and lower walls thereof and projecting beyond the forward 20 end thereof in position to be engaged by a cam member 102 that is integral with the frame 33 for the handle 32. A spring 103 disposed on the push rod 101 and seated in a socket 104 reacts against the head 105 of the 25 push rod 100 that is engaged by the cam member 102 so that the push rod 100 is normally maintained out of engagement with the push rod 98. Obviously, when the handle 32 is moved forwardly, the push rod 100 will be slidably moved along the guideway 101 to occasion a like movement of the push rod 98 and the operating arm 93 will be rocked about its pivotal connection so that the switch mechanism which has been 30 described in detail will be actuated to close a circuit and energize the incandescent lamps 72.

The film negative from which the prints are made is disposed across the transparency 11 so that the rays of light from the incandescent lamps 72-72 are projected therethrough to occasion the printing of the sensitized paper that is moved into contact therewith by the platen 19, I provide means 35 of maintaining individual film negatives or film negatives connected in strips in operative position and included in such means is a clip 106 that is pivoted at 107 for movement above the section 5 of the top and has an arm 40 108 rigidly connecting therewith to extend through a slot in the section 5 for pivotal connection with a link 109. The link 109 is connected by a rocker arm 110 with a rock shaft 111 that is journaled in brackets 112 45 secured to the under surface of the section 5. A spring 113 connects the arm 108 with a lug 114 secured to the under surface of the section 5 and exerts a tension on the clip 106 that tends to maintain the downwardly 50 curved end 115 thereof in position to clamp the film negative in adjusted position on a template 116 that is disposed on the upper surface of the section 5 and is special in construction as will be hereinafter set forth. 55 The rock shaft 111 is bent downwardly at 117 in position to be engaged by a laterally extending pin 118 (see Figures 1 and 6) carried by an arm 119 that is formed with an integral extension 120 pivoted at 121 to a bell crank lever 122 pivoted to a lug 122' at

123' secured to the under surface of the section 5. A link 123 connects the bell crank lever 122 at its free end with a flexible cable 124 that is passed around guide pulleys 125 and connected to a pedal (not shown). The 70 pedal is positioned for operation by an operator standing or sitting in front of the section 4 and when the pedal is depressed to pull the cable 124 downwardly, the lever 122 will be rocked about its pivotal connection 75 123', the pin 118 will thereupon be moved into engagement with the down-turned end of the rock shaft 111, rocking the latter and raising the clip 106 against the tension of the spring 113 to release the film negative. 80

The clip 106 is operated at each operation of the pedal. I provide an auxiliary clip 126 (see Figures 1 and 4) that is rigidly mounted on a shaft 127 journaled in a bearing that is secured to the upper surface of the section 5 to project into an angular opening 129 through the section 5. The shaft 127 has rigidly mounted thereon an operating arm 130 so that the clip 126 may be moved into inoperative position as indicated 85 by the dotted lines in Figure 4. A second arm 131 is rigidly mounted on a shaft 127 to project through the opening 129 for pivotal connection at 132 with a link 133 which is pivotally connected at 134 to a second link 135. The latter is pivoted at 136 to a hanger bracket 137 secured to the under surface of the section 5. A spring 138 connects at one end with a lug or bracket 139 secured to the under surface of the section 100 5 and at its other end to the pivot pin 134 connecting the links 133 and 135 so that the tension of the spring tends to maintain the clip 126 in either operative or inoperative position, as clearly shown in Figure 4 105. When the clip 126 is in operative position as indicated by the full lines in Figure 4, a cam member 140 that is formed integral with the extension 120 to the arm 119 will contact with the link 135 at each operation 110 of the arm 119 so that the clip 126 will be raised at each operation of the arm 119 occasioned by use of the pedal hereinbefore mentioned. The cam member 140 will not contact with the link 135 when the clip 126 115 is in inoperative position as indicated by the dotted lines in Figure 4.

In the event it is desired to print from uncut film negatives connected in a strip, an additional clamping member or clip 141 120 is provided (see Figures 1 and 5). The clamping member 141 is disposed in a slot 142 through the section 5 and is pivoted intermediately at 143 to a lug 144 secured to the under surface of the section 5 so that 125 the clamping member 141 may be moved about its pivot as illustrated in Figure 5. A pair of springs 145 connecting at one end with a pin 145' through the free end of the clamping member 141 have their other 130

ends secured at 146 to the lug 144 and thus tend to maintain the clamping member 141 in either operative position or inoperative position. When the clamping member 141 is in operative position, the lower end thereof is in position to be engaged by an off-set portion 147 of the rock shaft 111 so that the clamping member 141 will be raised into the position indicated by the full lines in Figure 5 when the rock shaft 111 is actuated by means of the pedal. When the clamping member 141 is in inoperative position, it will not be engaged by the off-set portion 147 of the rock shaft 111.

The device is intended for use in printing from film negatives commercially and it is therefore of advantage to provide a device capable of producing prints of commercial sizes and having margins varying in width as desired. To this end, I provide the template 116 which has the substantially V-shaped form illustrated, the angle at 148 being a right angle. The body portion of the template 116 is pivoted at 149 to an operating arm 150 that is pivoted at an end thereof to the upper surface of the section 5 as at 151. The arm 150 extends through a guide member 152 and is formed with a pointer 153 for positioning in alinement with graduation marks carried by the scale plate 154. The graduations are appropriately designated to indicate the widths of the margins that will be provided when the template 116 is positioned by operating the arm 150, as indicated by the pointer 153. The template 116 has a plurality of bolts or pins 155 each countersunk therein to extend through openings 156 in the wall of the section 5. The openings 156 are each enlarged at 157 to provide the socket for a disk or washer 158, having a guide slot, and a washer 159 slideable on the rod or bolt 155 is forced upwardly against the disk 158 by a spring 160 disposed on the bolt 155 between the washer 159 and a cooperating washer 161 on the bolt adjacent its lower end so that the template 116 will contact evenly and closely with the upper surface of the section 5. A nut 162 maintains the washer 161 in place and provides a means for adjusting the tension on the spring. A cooperating template 163 that has the general form of a rectangle cut away along the line 164 so that the angle at 165 is a right angle is formed with a plurality of openings 166 arranged in rows adjacent one end of the template and alined with slots 167 through the template adjacent its opposite end. The template 163 is supported on pins or bolts 168 and 169 which are similar to the bolts 155 and project upwardly through slots 170 and 171 in the section 5. The bolts 168 and 169 have their lower ends countersunk in an operating arm 172 which is irregular in shape, as clearly shown in Figure 3 and has arms supported by guide hangers 173 and a body portion 174 supported by a guide hanger 175. The body portion 174 is operatively connected by a bolt 176, extending through the section 5, with an operating arm 177. The latter is pivoted at 178 to the upper surface of the section 5 and extends through a guide 179 that is likewise secured to the section 5. The operating arm 177 is fashioned with an indicator 180 at its outer end arranged to move along a plate 181 secured to the upper surface of the section 5 and provided with a graduated scale 182 marked appropriately to denote the various sizes of commercial prints. It will be understood that the graduated plate 182 is identical with the plate 154 and that the graduations thereon correspond in value and arrangement. The irregular arm 172 that is held in contiguity to the under surface of the section 5 by the guide hangers 173 and 175 will be maintained thereagainst by disks indicated at 183 since these mechanisms are exactly identical with that previously described as maintaining the template 116 in contact with the upper surface of the section 5.

From the foregoing description of the various parts of the device, the operation thereof may be readily understood. The templates 116 and 163 are adjusted relative to each other to provide a rectangular opening of a suitable size for making a selected size of print. This is accomplished as follows: The template 163 is fashioned with an indicator 184 at one corner thereof. A plate 185 is secured to the upper surface of the section 5 in a predetermined position relative to the rectangular opening provided by the templates 116 and 163. The plate 185 has marked thereon a plurality of characters indicating the various sizes of commercial prints and the template is adjusted relative to the supporting bolts or pins 168 and 169, so that the indicator 184 points to a selected one of the characters on the plate 185, thereby insuring the desired size of print.

Adjustments to vary the margin of the prints $\frac{1}{16}$ of an inch at a time is accomplished by moving the operating arm 150 and the operating arm 177 until the indicator formed integral therewith point to like graduations on the plates 154 and 181. In service, the sensitized sheets to be printed are placed on the upper surface of the section 4 which is preferably supported at a distance from the floor so that the operator standing or sitting in front of the device can operate the pedal (not shown) which has been hereinbefore referred to, and at the same time conveniently manipulate the various elements of the mechanism carried by the section 5. Sheets of paper are successively placed in position on the template 19 and will be maintained thereon

by the clips 40, 40', 41, and 48 when the template is moved forwardly from its inoperative position against the rest 29. The selected sheet of sensitized paper will thus be pressed against a film negative that has been placed in position on the upper surface of the glass plate 11 and is maintained in that position by the clip 106 when the template 19 has been moved into the position illustrated in Figure 1. The handle 32 is then pulled forwardly to actuate the arm 93, thereby closing the switch mechanism shown in Figure 11, which has been described in detail, and closing a circuit to energize the incandescent lamps 72. The rays of light from the latter are projected upwardly through the glass plate to accomplish the printing of the sheet of sensitized paper held against the film negative. As the platen 19 is moved upwardly, the slip carrying member 36 will be moved toward the position indicated in Figure 7, thereby causing the clips 40, 40', 41 and 48 to disengage the printed sheet of paper which moves along the inclined upper surface of the section 5, through an opening 186 provided therein (see Figure 1). The top 7 of the supporting table is provided with an opening 187 beneath the opening 186 and the print falls through the opening 187 into a drawer 188 in the table. A closure 189 is provided for the opening 186 and this closure has rigidly secured thereto two spaced apart parallel rocker arms 190 which are rigidly mounted at one end on a rock shaft 191. The latter is journaled in hanger bearings 192 which are secured to the under surface of the section 5. The rock shaft 191 is bent laterally at 193 and curved into a substantially semi-elliptical shape, as best seen in Figure 1. A spring 194 secured to the under surface of the section 5 is arranged to react against the curved end portion of the rock shaft 191 to maintain the latter in constant engagement with a pivot pin 19 that engages a link 196 that is pivoted at 195 at one end to a lug 197 secured to the under surface of the section 5. The pivot pin 198 connects the link 196 at its other end to the adjacent end of the arm 119. When the arm 119 is moved by operation of the pedal, the link 196 will be moved from the position illustrated into a vertical position, thereby moving the closure 189 against a shoulder 199 or in closed position so that the upper surface of the closure is flush with the corresponding surface of the section 5.

The film negative is usually held in adjusted position by the clip 106. In case longer film negatives are used, as for instance when printing from a strip, the auxiliary clips 126 and 141 may be moved into position to clamp the film negative to the upper surface of the section 5, in the man-

ner which has hereinbefore been set forth. The auxiliary clips 126 and 141 will then be operated by the pedal by means of which the clip 106 and the closure 189 are operated. A spring 200 connected at one end 70 as at 201 with the arm 119 and at its other end with a lug 202 secured to the under surface of the section 5, returns the arm 119 to original position.

In commercial printing, it is desirable 75 that the prints from each negative bear a like number. In the embodiment of the invention illustrated, a type carrying frame 203 is arranged to enter an opening 204 through the platen 19 so that the surface 80 thereof carrying the type 205 is pressed against each print at the time of the printing operation to impress a selected number on that print. The type carrying frame 203 has a handle or arm 206 rigidly secured thereto at one end and this handle is rigidly mounted at its other end on a rock shaft 207 that is journaled in lugs 208 secured to the upper surface of the platen. A spring 209 mounted on the rock shaft 207 exerts a 85 tension thereon to maintain the rock shaft in the position illustrated in Figure 2, and to move the frame 203 from the position for changing the type as when the laterally extending portion 210 of the rock shaft 207 90 has been swung forwardly through 180 degrees from the position in which illustrated in Figure 2. The rock shaft 207 has loosely mounted thereon a link 211 which is pivoted at its other end as at 212 to a curved 100 arm 213 that is pivoted at 214 to a lug 215 secured to the upper surface of the section 5. A substantially U-shaped thrust member 216 has an end portion 217 projected through an opening 218 in the link 211 so 105 that the body portion of the member 216 is disposed in contact with the arm 206 that is rigid with the type carrying frame 203 when the type carrying frame 203 is in the position illustrated in Figure 2. When the U-shaped member 216 is in the position shown in Figure 10, the lug on the end of this member is not in contact with the type frame arm 206 and allows the type frame 110 to function properly, but if it is desired to make the numberer inoperative, then the member 216 is moved forward to the position shown in Figure 2. This causes the lug to raise the arm 206 and prevents the type frame 203 from descending far enough 115 into the opening 204 to make contact with the paper. Likewise, this same movement of the member 216 prevents contact of type with the ink pad 219 when the platen is in dotted position as shown in Figure 7. 120 When the platen is raised, the type carrying frame 203 will be moved from the position illustrated in Figure 2 on account of the thrust of the rod 216 thereagainst into the positions illustrated in Figure 7 so that 125 130

when the platen 19 is moved against the platen rest 29, the type 205 will be moved against an ink pad 219 that is disposed within a holder 220 having a central vertical shaft 221 rotatably mounted in laterally extending lugs 222 that are integral with a bracket 223. The latter is positioned on the upper surface of the section 5, being secured thereto at 224. A spring 225 mounted on the shaft 221 between the upper of the lugs 222 and the holder 220 presses the latter upwardly so that the type carrying frame and the inking pad 219 will operatively contact with one another. A nut 226 or the like carried at the end of the shaft 221 limits the movement of the latter upwardly.

The inking member is thus rotatable so that the type carrying surface of the numbering mechanism will contact with different portions of the ink pad at successive operations of the device.

It will be observed that the cabinet 12 is formed with ventilating openings 227 and 228.

25 I claim:

1. A printing machine comprising a work supporting member formed with an opening therethrough, a platen arranged for movement into position to cover said opening, a handle pivotally carried by the free end of said platen, normally de-energized means for projecting rays of light upwardly through said opening, and a switch operable connected to said handle only when said platen is in closed position whereby said handle may be swung for actuating the light projecting means.

2. A printing machine comprising a work supporting member formed with an opening therethrough, a transparent plate mounted in said opening, means for holding a film negative on said work supporting member in adjusted position relative to said transparent plate, means for moving a sensitized sheet into operative position with respect to said film negative, means for automatically releasing the sheet when said last named means is moved into inoperative position, means for conveying the sheet into a compartment, means for projecting rays of light through said negative to occasion the printing of the sensitized sheet, and means carried by the said means for moving the sensitized sheet for energizing the light projecting means, said last named means being operable only when said means for moving the sensitized sheet is in a certain position with respect to said film negative.

3. A printing machine comprising a table formed with an opening therethrough and with a transparent plate mounted in the opening, means for holding a film negative in adjusted position on said transparent plate, a platen movable into position to cover said transparent plate, means carried by

said platen for clamping a sensitized sheet to the face thereof in position to operatively contact with the film negative, said means being operated automatically to release the sheet when the platen is moved out of operative position, means for conveying the sheet into a compartment, and means for projecting rays of light upwardly through said transparent plate to occasion the printing of the sensitized sheet when superposed on the film negative.

4. A printing machine comprising a table formed with an opening therethrough and with a transparent plate mounted in the opening, means for holding a film negative in adjusted position on said transparent plate, a platen movable into position to cover said transparent plate, means carried by said platen for clamping a sensitized sheet to the face thereof in position to operatively contact with the film negative and for releasing the sheet when the platen is moved out of operative position, normally de-energized means for projecting rays of light upwardly through said transparent plate, means operable to occasion the energization of said light projecting means, and being a handle carried by the free end of said platen and operably connected to said means only when the platen is superposed on the transparent plate whereby the movement of said handle occasions the energization of the light projecting means.

5. A printing machine comprising an inclined table having an opening therethrough and a second opening at a lower level than the first named opening, a transparent plate mounted in said first named opening, means for holding a film negative in adjusted position on said transparent plate, means operable to project rays of light upwardly through said transparent sheet, a platen movable into position to cover said transparent plate, and means carried by said platen for clamping a sensitized sheet to the face thereof in position to operatively contact with the film negative when the platen is superposed on the transparent plate and for releasing the printed sheet when the platen is moved away from the transparent plate, so that the printed sheet will move along the inclined table and fall through the second named opening in the table, means for releasing said film negative holding means, and a door for said second named opening adapted to close when said last named means is actuated.

6. A printing machine comprising a work supporting member formed with an opening therethrough, a transparent plate mounted in said opening, means for holding a film negative on said work supporting member in adjusted position relative to said transparent plate, means operable to project rays of light upwardly through said transparent

plate, a platen movable into position to cover said transparent plate, means carried by said platen for clamping a sensitized sheet to the surface of the platen contacting the transparent plate, and means supported on said work supporting member relative to the transparent plate for determining the size of the exposed portion of the sensitized sheet superposed thereon when the platen is operated and for indicating the size on a scale, means for automatically disengaging said sheet when said platen is swung into inoperative position, a compartment, a door adapted to guide the released sheet into the compartment, and means for releasing the film negative, said last named means closing said door when operated.

7. A printing machine comprising a work supporting member formed with an opening therethrough, a transparent plate mounted in said opening, means for holding a film negative on said work supporting member in adjusted position relative to said transparent plate, means operable to project rays of light upwardly through said transparent plate, a platen movable into position to cover said transparent plate, means carried by said platen for clamping a sensitized sheet to the surface of the platen contacting the transparent plate, means covering marginal portions of the transparent plate to determine the size of the exposed portion of the sensitized print, and for indicating the size on a scale and means for movably supporting the margin defining means relative to the transparent plate so that the size of the opening defined thereby may be varied at will, means for automatically disengaging said sheet when said platen is swung into inoperative position, a compartment, a door adapted to guide the released sheet into the compartment, and means for releasing the film negative, said last named means closing said door when operated.

45 8. In a device of the type described, a frame, a platen pivotally carried by said frame, said platen adapted to be swung from a horizontal position into a vertical position, paper holding clips disposed on the outer edge of said platen and on a radially extending edge with respect to the pivotal axis of the platen, said clips being bent inwardly and being adapted to engage with the inner surface of said platen, and means for moving said clips out of engagement with the inner surface of said platen, said means swinging the clip carried by said radially extending side out of alinement with the inner surface of said platen.

60 9. In a device of the type described, a supporting frame, a platen pivotally carried by said frame, a U-shaped frame pivotally carried by said platen and having clips adapted to yieldingly engage with the inner

surface of said platen at points adjacent to the edge nearest the pivotal axis of said platen, an auxiliary clip carried by said second named frame and being adapted to yieldingly engage with the inner surface of said platen adjacent to a radially extending side thereof, and means for releasing said clips from said platen, said last named clip being adapted to also swing out of alinement with the inner surface of said platen when released.

10. A printing machine comprising a work supporting member, means for holding a film negative to said member, a platen adapted to grip and convey a sensitized paper into engagement with the negative, means for automatically releasing said paper when said platen is swung into inoperative position, a compartment disposed beneath said member, a door for guiding the released papers into said compartment, and means for releasing the film negative, said means being adapted to close said door.

11. In a printing machine, a member having an opening therethrough, a transparent plate mounted in the opening, a clip for clamping a film negative in adjusted position relative to the transparent plate, means carried by the member for normally clamping the film negative to the surface underlying the same, an auxiliary clamping clip, means carried by the member for supporting the auxiliary clamping clip so that the latter will be normally maintained in either operative or inoperative position, and means carried by the member and operable to move said first named clip and said auxiliary clip when the latter is in operative position to occasion the release of the film negative.

12. In a device of the type described, a supporting board having an opening therein, a platen adapted to be swung over said opening, tapered retaining clips carried by said platen, means actuated by the swinging of said platen for moving said clips into inoperative position immediately when said platen is moved away from said opening, and means carried by said board and being adapted to move said clips into inoperative position when said platen is moved into its furthest open position.

13. In a device of the type described, a supporting board, a platen hinged to said board, clips carried by said platen and being adapted to hold a piece of paper to the inner surface of said platen, a trigger carried by said platen and being adapted to instantly swing said clips into inoperative position when said platen is swung, and an auxiliary trigger carried by said board and being adapted to engage with said clips to throw said clips into inoperative position when said platen is swung into its furthest open position.

14. In a device of the type described, a base, two plates having spring qualities, a platen hinged to said plates, screws for rigidly securing the outer ends of said plates to said base, said plates having openings therein adjacent to the other ends of the plates, bolts slidably disposed in said openings, and springs mounted on the lower ends of said bolts for yieldingly holding the plates against the upper surface of the base. 10

PAUL ELGIN RIDINGS.
